UNITED STATES PATENT OFFICE.

EMIL HOLMQUIST, OF IRONWOOD, MICHIGAN.

RAIL-JOINT.

1,101,441.

Specification of Letters Patent. Patented June 23, 1914.

Application filed April 20, 1914. Serial No. 833,263.

To all whom it may concern:

Be it known that I, EMIL HOLMQUIST, a citizen of Finland, residing at Ironwood, in the county of Gogebic and State of Michigan, have invented certain new and useful Improvements in Rail-Joints; and I do declare the following to be a full, clear, and exact description of the invention, such as will enable others skilled in the art to which it appertains to make and use the same.

This invention relates to new and useful improvements in rail joints and the primary object of the invention is to provide a device of this character which will eliminate the use of bolts, nuts, fishplates and the like which are used on most rail joints now in use.

Still another object of the invention resides in providing a construction in connection with the rail sections which affords interlocking engagement between said sections.

A still further object resides in providing a simple, inexpensive and efficient construction which will enable the rail sections to be securely held together through the use thereof and which construction is not adapted for casual slipping engagement.

With these and other objects in view, my invention consists in the novel features of construction, combination and arrangement of parts as will be hereinafter referred to and more particularly pointed out in the specification and claims.

In the accompanying drawing forming a part of this application:—Figure 1 is a side elevation of a device constructed in accordance with my invention and showing one rail section about to be applied to the other section. Fig. 2 is a similar view showing the one rail section partially applied in connection with the other rail section, parts being broken away and parts in section to disclose the interlocking means.

Fig. 3 is a side elevation of the rail sections in their interlocked position. Fig. 4 is a horizontal section therethrough. Fig. 5 is a transverse section as seen on line 5—5, Fig. 1. Fig. 6 is a similar view as seen on line 6—6, Fig. 4. Fig. 7 is a similar view as seen on line 7—7 of Fig. 4.

In describing the invention I shall refer to the drawing in which similar reference characters designate corresponding parts throughout the several views and in which—

1 and 2 indicate respectively a pair of

rail sections which are adapted to be brought into abutting relation to one another and which are designed for interlocking engagement, each in itself forming a portion of my improved rail joint structure. The tread 3 of the rail section 1 terminates some distance short of the end of this section thus producing a web extension and the base flanges of this rail section extend to the end of the web. The web of this section is transversely enlarged in thickness as indicated at 4 and this enlarged portion extends to a point a short distance beyond the end of the tread 3. This enlarged web portion 4, however, is slotted on each side of the web extension said slotted portions being indicated at 5 and the same extend to points a short distance under the tread 3. The opposite rail section 2, has the web thereof increased or enlarged transversely as seen at 6 such portion extending for the greater portion of its length, and the base flanges of this section terminate some distance short of the end of said section, thus forming a shoulder 7 for abutment against the end of the section 1. The tread 8 of this rail section 2 terminates just short of the end of the web of this section thus providing a terminal engaging portion of the web at this section and the web of this section is slotted centrally as shown at 9 whereby to receive the web extension of the first mentioned section 1 therein. By slotting the complete web as described, the projecting portions of said web form, as stated above, terminal engaging portions indicated at 10 and these portions have the outer faces thereof slightly reduced whereby to be readily received in the slotted portions 5 of the first mentioned section. When so engaged, the outer faces of the web of the section 2 fit flush with the outer faces of the web or enlarged portion of the web on the section 1.

From the above description of the construction of my improved device it will be seen that when the two sections are brought together so that the web extension of the one section fits within the slotted portion of the web of the other section, the threads of the rail sections will be brought in abutting relation to one another to form substantially a continuous tread and the base flanges will also be brought into such relation as to form substantially continuous base flanges of the rail. In other words a complete rail is thus

formed but my invention primarily contemplates the provision of a means for locking the sections together automatically and providing a rail joint as the result thereof. To this end, the web of the rail section 1 at a point adjacent its outer end is provided with plate-like extensions indicated as 11. These plate-like extensions form locking lugs or the like thereon the same being formed integral with the faces of the web, and the inner directed edges of said extensions 11 are concaved as indicated at 12 while the outer directed edges thereof are convexed as shown at 13, the upper edges of these extensions 11 terminating just short of the upper edge of the web extension. At predetermined points on the web of the section 2, the walls of the slot therein are provided with grooves 14 which form channel ways for the reception 20 of said plate-like extensions 11 therein when said section 2 is applied to the section 1. These grooves 14 are designed coincident to the outline of the projections 11 so as to readily receive the latter thereon and when 25 said projections are properly received in said grooves or channels, it is obvious that said rail sections will be interlocked one with the other.

In operation, the rail section 2 is brought 30 in relation with respect to the rail section 1 so as to receive therein the treadless web of the latter. In order to accomplish this result, the section 2 must be applied to the section 1 from above and when so applied, the 35 terminal engaging portions of the section 2 are designed for reception in the spaced longitudinal channels or the like in the section 1. The treadless web of the section 1 is received first in the outer end portion of the 40 slotted web of said section 2 whereupon the latter is moved longitudinally of the section 1 until the tread thereof abuts the terminal of the tread of the section 1. At such time, it will be seen that the terminal engaging 45 portions of said section 2 will be received in the longitudinal channels of the section 1 whereupon said section 2 is lowered, said lowering being readily made possible through the beveling of the terminal 50 engaging portions. In the lowering of this section 2 it will be seen that the projections 11 on the faces of the web section 1 will be received in the grooves or channels 14 of the slotted web of said section 2. When this rail 55 section 2 has been lowered, the shortened base flange thereof will abut the base flange of the rail section 1 and a complete rail will thus be formed, the sections of which are so interlocked one with the other as to prevent 60 any possible disengagement thereof. The interlocking of the sections of the rail is such as to prevent any possible lateral or longitudinal movement thereof and the abutment between the sections is so close as to provide 65 a perfect fitting rail joint whereby the usual

noise incident to the rolling of cars over joints in rails will be eliminated in the use of this device.

From the foregoing it will be seen that I have provided a simple, inexpensive, and efficient means for carrying out the objects of the invention and while I have particularly described the elements best adapted to perform the functions set forth, it is obvious that various changes in form, proportion and the minor details of construction may be resorted to, within the scope of the appended claims, without departing from the spirit or sacrificing any of the principles of the invention.

Having thus described my invention, what I claim is:

1. In a rail joint, a rail section having the tread terminating short of the end thereof, the web thereof having spaced longitudinal channels therein adjacent the end of the tread, a complementary rail section having the base flanges thereof terminating short of the end thereof, the web of said complementary section being slotted for the greater portion of its length to receive the treadless web of the first mentioned rail section therein, terminal extensions on said slotted web for reception in the spaced longitudinal channels of the first mentioned section, and interlocking means between the webs of said sections.

2. In a rail joint, a rail section having the tread terminating short of the end thereof, the web adjacent the end of the tread being transversely increased and provided with spaced longitudinal channels, a complementary rail section having the base flanges thereof terminating short of one end of the same and also having the web increased transversely and slotted for a portion of its length to receive the treadless web of the other section therein, the end of said slotted web extending beyond the end of said rail to form terminal engaging portions for reception in the spaced longitudinal channels of the first mentioned section, and interlocking means between the webs of said sections.

3. In a rail joint, a rail section having the tread terminating short of the end thereof, the web adjacent the end of the tread being transversely increased and provided with spaced longitudinal channels, said webs with the channels therein extending just beyond the termination of said tread, a complementary section having the base flanges thereof terminating short of one end of the same and also having the web increased transversely and slotted for a portion of its length to receive the treadless web of the other section therein, the end of said slotted web extending beyond the end of the rail and reduced from the outer faces thereof to form terminal engaging ribs for reception in the

spaced longitudinal channels of the first mentioned section, and means formed in connection with said webs for the interlocking of said sections whereby to prevent the 5 longitudinal movement of the same with respect to one another.

4. In a rail joint, a rail section having the tread terminating short of one end thereof, the web of said section adjacent the end of the tread being provided with spaced longitudinal channels, a complementary section having the base flanges thereof terminating short of one end, the web of said last mentioned section 15 being slotted to receive the treadless web of the first mentioned section therein, terminal extensions formed on said complementary section for reception in the spaced longitudinal channels of the first mentioned section, 20 the inner walls of the slotted web of said complementary section being provided with a pair of oppositely spaced grooves, and projections formed on the outer faces of the web of the first mentioned section adapted 25 to be received in the grooves of said complementary section, whereby to interlock said sections one with the other.

5. In a rail joint, a rail section having a tread terminating short of one end thereof, 30 the web of said rail section being increased adjacent the termination of the tread and provided with a pair of spaced longitudinal channels, plate-like projections formed on the outer faces of the web of said section adjacent 35 the outer edge thereof, the inner edges of said projections being concaved and the outer edges thereof being convexed, a complementary rail section having the base flanges thereof terminating short of one end 40 of the same, the web of said last mentioned section being also increased transversely and slotted for the greater portion of its length to receive the treadless web of the first mentioned section therein, the inner walls of the 45 slotted web of said last mentioned section being also increased transversely, the inner

walls of the slotted web of said last mentioned section being provided with grooves adjacent the inner ends of said slotted portion, said grooves being designed coincident 50 with the outline of said projections on the other section for the reception of the latter therein, and terminal projections formed on the web of the last mentioned section adapted to be received in the longitudinal 55 channels of the first mentioned section.

6. In a rail joint, a rail section having a tread terminating short of one end thereof, the web of said section adjacent the end of the tread thereof being transversely increased and 60 provided with spaced longitudinal channels, a complementary section having the base flanges thereof terminating short of one end of the same and also having the web increased transversely and slotted for a portion 65 of its length to receive the treadless web of the other section therein, the end of said slotted web extending beyond the end of the rail to form terminal engaging plates to be received in the spaced channels of the 70 first mentioned section, the inner walls of the slotted portion of said complementary section being provided with a pair of oppositely spacing grooves, the end walls of said grooves being designed arcuately, and 75 plate-like projections formed on the outer faces of the web of the first mentioned section adapted to be received in the grooves of the complementary section, the edges of said projections being designed coincident 80 to the outline of the end walls of said grooves whereby said projections will fit snugly in the grooves and form interlocking means between the sections of the rails.

In testimony whereof I have hereunto set 85 my hand in presence of two subscribing witnesses.

EMIL HOLMQUIST.
